UNITED STATES PATENT OFFICE

LYNN G. LINDSAY, OF NEAR DAYTON, OHIO, ASSIGNOR TO TRUPAR MANUFACTURING COMPANY, OF DAYTON, OHIO, A CORPORATION OF OHIO

LIQUID COOLER FOR REFRIGERATORS

Application filed August 11, 1931. Serial No. 556,397.

This invention relates to new and useful improvements in liquid coolers for refrigerators.

It is the principal object of my invention 5 to provide for attachment to the inside portion of the door of a refrigerator, a liquid cooling container from which the cooled liquid may be withdrawn as desired from a faucet on the front side of the door. The 10 container is particularly adapted for cooling water, and being carried by the refrigerator door, it does not interfere with the shelves, and at the same time makes available for the reception of other articles, the space which it 15 would occupy if it were placed within the refrigerator proper.

Other important and incidental objects will be brought out in the following specification and particularly set forth in the subjoined 20 claim.

In the accompanying drawing illustrating 25 my invention, Figure 1 is a front view of a refrigerator casing having a hinged door to the rear side of which my liquid cooling container is secured. Figure 2 is a side view of 30 the door, showing the attached liquid cooling container and faucet. Figure 3 is a top plan view of the same. And Figure 4 is a cross sectional view taken on the line 4—4 of Figure 3, showing the removable cover for 35 the cooling container.

Referring to the accompanying drawing, the numeral 1 designates a conventional refrigerator casing mounted upon feet 2 and 40 provided with a side-hinged door 3. Secured to the upper inside portion of said door, by welding or otherwise, is a preferably rectangular, shallow liquid container 4 formed of suitable metal. At its upper rear middle 45 part this container is formed with a funnel portion 5 to receive a liquid such as water for cooling through exposure to the refrigerating medium (not shown) within the casing 1. The upper end of this container, including the funnel portion 5, is closed by a removable cover 6. (See Figures 2 and 4.)

Communicating with the bottom portion 50 of the container 1, and projecting therefrom through a horizontal hole in the door 3, is a liquid discharge tube 7. Connected to the

outer end of this tube, on the front side of the door, is a conventional faucet 8 through which the cooled liquid may be withdrawn as desired.

It is thus seen that I have provided a container secured within a small space to the inside part of a refrigerator door, for cooling a liquid such as water that may be conveniently withdrawn, as desired, from a faucet on the 55 front side of the door.

Having described my invention, I claim: 60 In a refrigerator casing having a door to afford access to the interior thereof, an elongated shallow liquid container secured to the upper inside portion of said door, a funnel 65 inlet portion flared outwardly from the top part of the front wall of the container, a tube projecting from the bottom of said container through said door, and a faucet secured to said tube on the front side of said 70 door.

In testimony whereof I have hereunto set my hand this 10th day of August, 1931.

LYNN G. LINDSAY.
